CLAIM

We claim the ornamental design for a pipe coupling segment, as shown and described.

DESCRIPTION

FIG. 1 is a perspective view of our design for a pipe coupling segment;

FIG. 2 is a front view of the design for the pipe coupling segment shown in FIG. 1, the rear view being the same;
FIG. 3 is a top view of the design for the pipe coupling segment shown in FIG. 1;

FIG. 4 is a bottom view of the design for the pipe coupling segment shown in FIG. 1;

FIG. 5 is a left side view of the design for the pipe coupling segment shown in FIG. 1; and,

FIG. 6 is a right side view of the design for the pipe coupling segment shown in FIG. 1.

The broken lines depict portions of the pipe coupling segment that form no part of the claimed design.
